UNITED STATES PATENT OFFICE.

PAUL B. PARKS, OF OAK PARK, AND JOHN VAN VULPEN, OF CHICAGO, ILLINOIS, AS-SIGNORS TO VAPOR CAR HEATING COMPANY, INC., OF CHICAGO, ILLINOIS, A CORPORATION OF NEW YORK.

SWITCH-OPERATING MECHANISM.

Original application filed May 19, 1923, Serial No. 640,133. Divided and this application filed April 18, 1924. Serial No. 707,434.

To all whom it may concern:

Be it known that we, PAUL B. PARKS and JOHN VAN VULPEN, citizens of the United States, residing at Oak Park, Illinois, and Chicago, Illinois, respectively, have invented certain new and useful Improvements in Switch-Operating Mechanism, of which the following is a specification.

Our invention relates to mechanism for giving intermittent movements of rotation alternately in opposite directions to a revolute element, for example, to the stem or spindle of a valve, such as is used in the car heating system disclosed in our co-pending application Serial No. 640,133 filed May 19, 1923, of which application this application is a division. The invention contemplates the employment of two alternately energized electric motors, solenoids, for example, for giving the spindle its rotations in opposite directions, and of a limit switch operated by the movements of said spindle for breaking the circuit through each solenoid as soon as the movement of the valve produced by the energization of that solenoid has been accomplished.

One of the principal objects of the invention is to provide certain improvements in a circuit breaker of this type to the end that the device may be more durable, reliable and efficient in its operation than devices of this type heretofore used.

A further object is to improve generally upon the mechanism by which the desired movements of the valve or other revolute element are accomplished.

The invention is illustrated, in certain preferred embodiments, in the accompanying drawings, wherein—

40 Fig. 1 is a plan view of the valve operating mechanism with the cover or housing plate in section.

Fig. 2 is a vertical sectional view on line 2-2 of Fig. 1.

45 Fig. 3 is a vertical sectional view on line 3-3 of Fig. 1.

Fig. 4 is a detail side view of the valve stem operating lever modified to provide for adjustment.

50 Fig. 5 is a plan view similar to Fig. 1, embodying the form of operating lever shown in Fig. 4, and

Fig. 6 is a fragmentary plan view illus-

trating a modified and preferred form of brush for the limit switch.

Referring to the drawings, B designates the valve as a whole, the casing of which is indicated by numeral 50 and the revoluble valve body by numeral 51. The valve body is provided with a stem 72 suitably engaged with said valve body so that the two rotate together. Stem 72 is formed at its upper end with a portion 97 which is approximately square in cross section but with one surface 98 slightly curved. To this part of the stem is fixed a lever F formed with a boss 99 having an opening corresponding to the shape of the portion 97 of the valve stem. This boss is split at 100 and is clamped to the stem by a screw 101. The rounded surface 98 on the stem and the corresponding surface on the lever are to insure a proper angular position as between the valve and its operating lever in assembling the parts. The lever F has a bulging portion 102 with curved edges 103, 104. This part of the lever lies between a pair of collars 105, 106 on the common core E of two solenoid coils C and D. The coils, core and other mechanism to be described, located on the top of the valve, are contained in a housing 107 which comprises a removable cover plate 108 having an opening at 109 for the outer end 110 of the lever F, which lever projects out of the housing over a plate 111 bearing the legends "On" and "Off." In case of emergency the lever F may be turned by hand.

When coil C is energized and the core E is drawn in this direction, it is the part 90 of the collar 106 most remote from the axis of the valve spindle which, during the first part of the movement of the core, bears against the lever F. This means that the leverage for rotating the valve is greatest 95 during the first part of the travel of the core. This is important because it requires more power to start the valve than to turn it after its movement has been initiated, and because the power which the solenoid can exert at the beginning of the movement of the core is less than the power exerted near the end of the travel of the core. As the core moves into the coil C the point of bearing between the collar 106 and the lever F 100 shifts to the other side of the collar so that

when the core is moved in the other direction by coil D the leverage will be at a maximum during the initial movements of the core, that is to say, collar 105 will engage 5 the lever at a point as remote as possible from the axis of rotation of the valve.

Coils C and D are energized alternately and a limit switch is provided for shutting off current from the energized coil as soon 10 as the valve movement produced by said coil is complete. This limit switch is constructed as follows: 112, 113 are a pair of insulating blocks secured by bolts 114 to the portions 115, 116 of the housing enclosing coils C and D, respectively. On the top 15 of block 112 is a contact plate 117 provided with a downturned flange 118 for a securing bolt 119. The contact spring 29, the end of which is V-shaped as shown in Fig. 2, is secured to the plate 117 by screw 120, the rear edge of the spring being bent over the edge of the contact plate 117, as indicated at 121, and fitted into a recess in the block. Another contact plate 122 is secured 20 to the upper face of block 112 by screws 123, 124 which serve as binding posts for electrical connections to be described. To the bottom of block 112 is secured a contact plate 125 similar to plate 117 and to 25 this plate is secured by screw 126 the spring contact 31 having an upwardly bent portion as shown in Fig. 2. Contact plates 127, 128, corresponding to contact plates 117, 122, are secured to the upper face of block 113 30 and the contact spring 33 is fastened by screw 129 to the plate 127. The movable circuit breaking element of the limit switch 35 consists of a cylindrical body 30 formed with a pair of studs or stems 131 adapted 40 to extend, rotatably, into perforations 132 of the blocks 112, 113. The circuit breaking member is formed with a circumferential groove 133, the side faces 134 of which are preferably beveled as shown in Fig. 2. The contact spring 31 bears against the circuit breaker 30 in all positions of the latter. The circuit breaking member 30 is adapted 45 to contact alternately with springs 29 and 33 as said member is moved back and forth 50 between said blocks. For effecting this movement of the circuit breaker member 30, blade 135 of insulating material is secured by screws 136 in the bifurcated end 137 of the lever F. This blade projects into the 55 groove 133 of member 30 so that when the lever F is given an angular movement the blade imparts to the circuit breaking member a longitudinal movement and also a certain amount of rotation. By this arrangement the wear on movable contact member is distributed around its entire outer surface and there is a wiping engagement between the movable contact members and the spring which tends to keep all of the contact 60 surfaces clear.

Supply wire 28 extends to binding post 123 and the ends of coil C are connected with binding post 124 by wire 28^a and with a binding post 138 on contact plate 117 by wire 32^a. Wire 32 is connected to a binding post 139 on an ear 140 formed on the contact plate 125. Wire 35 is connected to a binding post 141 on the contact plate 128 and the ends of the coil D are connected to binding posts 142, 143 on the contact 75 plates 127 and 128, respectively, by wires 32^b and 35^a. The wires leading into the housing may be enclosed in a pipe 144 threaded into a coupling 145 secured to the casing 80 of the valve.

A modification in respect to the construction of the operating lever is illustrated in Figs. 4 and 5, in which 146 is the valve stem and 147 the operating lever fixed to the stem by a nut 148 and lock washer 149. 150 is a member perforated at 151 to fit the reduced upper end 152 of the valve stem 146. The member 150 is channel-shaped at one end, as indicated at 153, to receive the blade 154 of insulating material adapted to engage the circumferential groove in the movable element of the circuit breaker. The other end of member 150 is formed with a slot 155 through which projects a set screw 156 whereby the angular position of the member 150 on member 147 may be adjusted.

Fig. 6 shows a modified form of upper brush for the limit switch. The brush consists of a plate 158 having a downturned arm 159 to bear against the side of the cylindrical switch member 30, the arm 159 being formed with a forwardly projecting deflected lip 160 and a rearwardly projecting lug 161 adapted to enter a slot in the block 118^a to which the brush is secured, the lug 161 serving by its engagement with the block to keep the arm 159 in spring contact with the switch member 30.

The construction of the valve forms no part of the invention herein claimed, being the subject matter of a co-pending application filed April 18, 1924, Serial No. 707,435.

Operation.

With the parts of the circuit breaker in the positions shown in Fig. 1 and 2, the closing of the circuit through wires 28, 32, energizes solenoid C which attracts core E so as to impart angular movement to lever F and corresponding movement of rotation to the stem 72 of the valve body 57. The engagement of the blade 135 on lever F with the groove 133 of the movable element of the circuit breaker, imparts a longitudinal movement to said movable element which, at the end of the movement of rotation of the valve body breaks the aforementioned circuit as between contact spring 130

29 and movable member 30. When the valve is to be given movement of rotation in the opposite direction the circuit is closed between wires 35 and 32 and similar movements take place, as just described, but in the opposite directions. The character of the engagement between blade 135 and circuit breaker 30 produces a rotary movement of the latter as well as a longitudinal movement. This distributes the wear on member 30 besides producing rubbing or wiping movements as between member 30 and the contact springs, which movements tend to keep the contact surfaces clean. The modification of Fig. 6 provides for maintaining a certain pressure as between the contact spring and movable member 30. The arrangements of Figs. 4 and 5 permit an adjustment of the operating blade 135 independent of the angular position of the lever which is a matter of convenience in assembly of the parts of the apparatus.

We claim:

1. In combination with a rotary member, 25 a lever carried by said member and a circuit breaker comprising a fixed contact, a revolvably mounted longitudinally movable cylindrical contact, and means on said lever which engages said movable contact so as 30 to revolve it while moving it longitudinally.

2. In combination with a rotary member, a lever carried by said member and a circuit breaker comprising a fixed contact, a revolvably mounted longitudinally movable 35 cylindrical contact having a transverse groove therein, and a blade on said lever which projects into said groove so that angular movements of the lever impart longitudinal and rotary movement to the movable 40 contact.

3. In combination with a rotary member, a lever carried by said member and a circuit breaker comprising a fixed spring contact, a revolvably mounted longitudinally 45 movable cylindrical contact, and means on said lever which engages said movable contact so as to revolve it while moving it longitudinally.

4. In combination with a rotary member, 50 a lever carried by said member and a circuit breaker comprising a fixed spring contact, a revolvably mounted longitudinally movable cylindrical contact arranged at substantially right angles to the lever at the 55 middle position of the latter, said movable contact being formed with a transverse circumferential groove, and a blade on the lever to extend into said groove.

5. In combination with a rotary member, 60 a lever carried by the member and a circuit breaker comprising spaced spring contacts, a cylindrical contact mounted so as to be revolvable and movable longitudinally into and out of engagement with said fixed 65 contacts two at a time and formed with a

transverse circumferential groove having beveled side faces, and a blade on said lever to project into said groove for imparting longitudinal and rotary movements to said movable contacts.

6. In combination with a rotary member, a lever carried by the member and a circuit breaker comprising spaced spring contacts, a cylindrical contact mounted so as to be revolvable and movable longitudinally into 70 and out of engagement with said fixed contacts two at a time and formed with a transverse circumferential groove having beveled side faces, a blade on said lever to project into said groove for imparting longitudinal and rotary movements to said movable contacts, a pair of solenoids for rotating said rotary member and shifting said movable contact, and a common core for said solenoids provided with spaced collars between which said lever extends, the lever being formed between said collars with an enlargement having curved edges whereby at each valve movement the part of the collar most remote from the axis of rotation 80 of the valve bears against the lever initially.

7. A circuit breaker comprising a fixed contact, a revolvble and longitudinally movable contact formed with a circumferential 85 groove and a lever transversely arranged with respect to the movable contact for moving the latter into and out of engagement with the fixed contact having a member which enters said groove.

8. A circuit breaker comprising a fixed contact, a revolvble and longitudinally movable contact formed with a pair of opposite conical surfaces, and a lever transversely arranged with respect to the movable contact having a member to engage said conical surfaces for imparting longitudinal and 95 rotary movements to said movable contact.

9. A circuit breaker comprising spaced, fixed spring contacts, a revolvble and longitudinally movable contact adapted to engage with said spring contacts two at a time and formed with a circumferential groove having beveled sides, and a lever transversely arranged with respect to said movable contact, having a member which enters said 100 groove and engages the beveled sides of said groove.

10. A circuit breaker comprising a longitudinally movable contact, a spring contact which bears against the movable contact in all positions of the latter, a pair of spaced spring contacts which bear upon the movable contact, one when the movable contact is in one of its extreme positions and the other when the movable contact is in the other extreme position, and means for imparting longitudinal and rotary movements to the movable contact.

11. A circuit breaker comprising a longi-

tudinally movable contact, a spring contact which bears against the movable contact in all positions of the latter, a pair of spaced spring contacts which bear upon the movable contact, one when the movable contact is in one of its extreme positions and the other when the movable contact is in the other extreme position, said movable contact being rotatably mounted and formed 10 with a circumferential groove, and a lever having a member which engages the groove to impart longitudinal movement to said movable contact.

12. A circuit breaker comprising a longitudinally movable contact, a spring contact which bears against the movable contact in all positions of the latter, a pair of spaced spring contacts which bear upon the movable contact, one when the movable contact 15 is in one of its extreme positions and the other when the movable contact is in the other extreme position, said movable contact being rotatably mounted and formed with a circumferential groove, and a lever 20 having a member which engages the groove to impart movements to said movable contact.

13. A circuit breaker comprising a longitudinally movable contact, a spring contact 25 which bears against the movable contact

in all positions of the latter, a pair of spaced spring contacts which bear upon the movable contact, one when the movable contact is in one of its extreme positions and the other when the movable contact is in the 35 other extreme position, said movable contact being rotatably mounted and formed with a circumferential groove, a lever and a member angularly adjustable on said lever which engages said groove to impart movements to said movable contact. 40

14. A circuit breaker comprising a longitudinally movable contact, a pair of spaced contacts against which the movable contact is brought to bear at opposite ends of its 45 travel, respectively, a lever, and an angularly adjustable member on said lever to engage the movable contact for imparting movements to the same.

15. A circuit breaker comprising a rotatable and longitudinally movable contact formed with a circumferential groove, a pair of spaced contacts against which said movable contact is brought to bear at opposite ends of its travel, respectively, a lever, and an angularly adjustable member on said 50 lever to engage the movable contact for imparting movements to the same.

PAUL B. PARKS.
JOHN VAN VULPEN.
